HAULAGE MECHANISM

Filed April 8, 1922

UNITED STATES PATENT OFFICE

ROBERT C. OSGOOD, OF CLAREMONT, NEW HAMPSHIRE, ASSIGNOR TO SULLIVAN MACHINERY COMPANY, A CORPORATION OF MASSACHUSETTS

HAULAGE MECHANISM

Application filed April 8, 1922. Serial No. 550,888.

My invention relates to haulage mechanism.

An object of my invention is to provide an improved hoisting or haulage mechanism. Another object of my invention is to provide an improved mechanism of the type in which the motor is enclosed within the hoist drum. A further object of my invention is to provide an improved haulage mechanism of the type in which the driving motor is enclosed in the drum and the drum itself shall constitute one haulage means, while auxiliary haulage means is also provided. Other objects and advantages of my invention will hereinafter more fully appear.

In the accompanying drawing I have shown for purposes of illustration one form which my invention may assume in practice.

In this drawing,—

The view is a central vertical section through the illustrative embodiment of my improved mechanism.

In its illustrative form my improved mechanism is disclosed as comprising a rotating drum 1 journaled in a U-shaped support 2. The drum comprises a central portion 3 and end portions 4 and 5, the latter being provided with stub shafts 6 and 7, of which the former is journaled in a standard or upstanding hanger 8 forming a part of the frame 2, while the latter is journaled within an annular member 9 which is in turn journaled in a standard or upstanding hanger 10 arranged at the opposite end of the frame 2. My improved haulage mechanism, as shown herein, is of the fluid pressure driven type; and enclosed within the central section 3 of the drum is an improved driving motor comprising a pair of rotors 12 and 13 journaled in the head 4 and in an intermediate head 14 which is arranged within the drum and spaced a short distance from the head 5. The rotors 12 and 13 are provided with intermeshing tooth blades 15 which cooperate to form pockets or chambers which expand in volume as

rotation of the rotors takes place, and suitable inlet means connected with a source of fluid pressure 16 is arranged as indicated at 17 to supply this fluid under pressure to the expanding pockets at their points of inception. The exhaust of fluid takes place to

chambers 18 and 19 at opposite ends of the rotors; and the expanded fluid will be freed from the interior of the drum in any suitable manner, as by ports in the head 4, not shown. The rotor 12 is provided with a shaft 20 extending through the intermediate head 14 and carrying a driving pinion 21 which drives a larger gear 22 fixed to a shaft 23 which is journaled in the heads 14 and 5 and which carries a smaller pinion 24 meshing with and driving a larger gear 25. The latter is fixed to a rotatable shaft 26 which extends through the head 5 and at its opposite end carries a pinion 27 which in turn meshes with a gear 28 journaled on a stud or stub shaft 29 fixed to the head 5 adjacent the periphery thereof. The gear 28 meshes with an internal gear 30 formed at the inside of a collar 31 which is supported upon a plate 32 secured to or, as shown herein, formed integral with the sleeve 9.

Suitable braking means comprising a braking surface 33 formed upon the collar 31, a brake band 34, and manual control means 35 therefor serves to hold the internal gear 30 against rotation and to cause rotation of the drum. At the opposite end of the drum from the brake band described is a flange 36 having a braking surface 37 formed thereon which is engageable by a brake band 38 having manual operating means 39. When the brake band 38 is applied and the brake band 34 released, the drum will be held stationary and the member 31 rotated as will be shortly made clear. Secured to the sleeve 9 outside of the hanger 10 is a winding member 40 over which a rope may be wound in such a manner as to permit it to be hauled in, the member 40 corresponding in its operation to a capstan disposed in a horizontal position. For convenience, in certain of the appended claims, the term capstan is, therefore, used.

From the foregoing description the mode of operation of this mechanism will be readily apparent. When the brake band 34 is applied, the member 31 will be held against rotation and accordingly the internal gear 30 will be stationary. Upon supply of fluid to the rotors 12 and 13, they will revolve, causing rotation of the train of gears 21, 22, 100

24, 25, 27 and 28, the last of which meshes with the internal gear 30. Rotation of the drum will therefore be caused to take place, as rotation of the gear 30 can only occur when 5 accompanied by bodily movement of its pivot around the axis of the shaft 7. It will therefore be evident that the drum 1 will wind in a flexible member which may be secured thereto, as herein the member 50. Unwinding of 10 the rope 50 may be accomplished by releasing the brake band 34 under which circumstances the member 31 will rotate with the drum when the air is cut off, or at a greater speed if the air is still supplied to the motor. If it is desired to employ the winding member 40, the 15 brake band 38 may be applied and the brake band 34 released, which will result in the rotation of the member 40; and by taking one or two turns about this member, a large 20 weight can be easily handled.

If it be desired to use this apparatus for the operation of a jib crane, it may be readily employed with such a device by locating a snubbing post adjacent the member 40 and 25 passing the rope which is to shift the boom of the crane about the winding member 40. It will then be possible to raise or swing the boom as desired by applying the brake member 38 and releasing the brake band 33. 30 When the boom has been moved to the desired position, the rope wound upon the member 40 may be either fastened over the snubbing post by half hitches or may be released; and either before or after movement of 35 the boom, as the case may be, application of the brake band 34 and release of the brake band 38 will effect raising of the load to be handled. The device may also be used to handle submarine drills, the main drum 40 handling the drill itself while the smaller member 40 can be used to handle drill steels or vice versa.

While I have in this application specifically described one form which my invention may 45 assume in practice, it will be understood that this form of the same is shown for purposes of illustration and that the invention may be modified and embodied in various other forms without departing from its spirit or the scope 50 of the appended claims.

What I claim as new and desire to secure by Letters Patent is:

55 1. A hoisting mechanism including a winding drum, a driving motor therefor enclosed therein, means for effecting rotation of said winding drum by said motor comprising a gear rotatably supported on an axis fixed with respect to the winding drum and parallel to but offset from the axis of the latter, and a 60 member comprising an internal gear surrounding said first mentioned gear and cooperating therewith, and means for supporting said member and internal gear for rotation upon an axis coaxial with the axis of the 65 winding drum, said member carrying a sup-

plemental winding member beyond said supporting means.

2. In a hoisting mechanism, a frame having upstanding hangers thereon, a member journaled in one of said hangers and having a capstan detachably carried thereby, a drum journaled at its opposite ends respectively in the other of said hangers and in said member, and means for alternatively driving said drum and capstan including a gear cooperating with said member and carried by said drum on an axis parallel to the drum axis. 70

3. In a hoisting mechanism, a frame having upstanding hangers thereon, a member journaled in one of said hangers and having a capstan carried thereby at the opposite side of said hanger from said member and removable therefrom without disturbing the remaining elements, a drum journaled at its opposite ends respectively in the other of said hangers and in said member, a motor in said drum, means for braking said drum and member for alternatively driving said drum and capstan, and a gear cooperating with said member and carried by said drum on an axis parallel to the drum axis, said motor being connected in driving relation with said gear. 80

4. In a hoisting mechanism, a rotatable member having a capstan with a free end, said capstan being rigidly secured to said member and removable longitudinally therefrom, means for journaling said member, a drum, means for journaling one end of said drum in said member, and means for alternatively driving said drum and capstan including a driving gear disposed on a longitudinally extending axis, and a gear meshing with said driving gear and carried by said member and surrounding said driving gear. 90

5. In a hoisting mechanism, a hanger, a 95 rotatable member journaled in and disposed on one side of said hanger, a capstan carried by and having a fixed angular relation to said member, said capstan being disposed on the opposite side of said hanger, said hanger cooperating with said member and capstan to prevent longitudinal movement thereof, a drum aligned with said capstan, said drum being rotatable relative to said member, means for supporting said drum including said 100 hanger, and means operatively connecting said drum and rotatable member including a gear carried by said drum and rotatable on a longitudinal axis, said means being adapted to drive alternatively said drum and capstan. 110

115 6. In a hoist, a winding drum, a driving motor therefor enclosed therein and rotatable therewith, driving connections between said drum and motor including a reaction gear arranged coaxially with the drum axis and 120 adapted to be held stationary to effect drum rotation or to be released to permit running of said motor while said drum remains stationary, and a supplemental winding member attached to said reaction gear and rotat- 125 130

able therewith, said winding member having a free outer end.

7. In a hoist, a supporting frame having end brackets, a winding drum rotatably mounted at its ends in said brackets, a driving motor for said drum enclosed therein and rotatable therewith, driving connections between said drum and motor including a reaction gear arranged coaxially with the drum axis and adapted to be held stationary to effect drum rotation or to be released to permit running of said motor while said drum remains stationary, and a supplemental winding member attached to said reaction gear and rotatable therewith, said supplemental winding member being supported by said reaction gear beyond the adjacent supporting bracket and having a free outer end.

In testimony whereof I affix my signature.
